UNITED STATES PATENT OFFICE

118,828

DESIGN FOR A COMBINED FRONT FORK AND FENDER FOR VELOCIPEDES

John R. Morgan, Oak Park, Ill., assignor to Sears,
Roebuck and Co., Chicago, Ill., a corporation of
New York

Application November 18, 1938, Serial No. 81,201

Term of patent 3½ years

To all whom it may concern:

Be it known that I, John R. Morgan, a citizen
of the Republic of Guatemala, residing in Oak
Park, in the county of Cook and State of Illinois,
have invented a new, original, and ornamental
Design for a Combined Front Fork and Fender
for Velocipedes, of which the following is a speci-
fication, reference being had to the accompanying
drawing, forming a part thereof.

Fig. 1 is a top plan view of the fender shown
in Figs. 2-4.

Fig. 2 is a side elevational view of the combined
front fork and fender showing my new design.

Fig. 3 is a front elevational view taken from
plane 3—3 of Fig. 2.

Fig. 4 is a fragmentary elevational view show-
ing the lower portion of the fender.

I claim:

The ornamental design for a combined front
fork and fender for velocipedes, as shown.

JOHN R. MORGAN.
